UNITED STATES PATENT OFFICE.

DAVID S. THOMAS, OF NORTH PLATTE, NEBRASKA.

AIRSHIP.

1,064,872.

Specification of Letters Patent. Patented June 17, 1913.

Application filed January 23, 1913. Serial No. 743,822.

To all whom it may concern:

Be it known that I, DAVID S. THOMAS, a citizen of the United States, residing at North Platte, in the county of Lincoln and State of Nebraska, have invented certain new and useful Improvements in Airships, of which the following is a specification.

My present invention relates to improvements in airships of the type known as propelled wing flying machines.

The object of the invention is the improvement of certain parts of flying machines whereby simplicity of construction and operation are attained, an efficient machine is produced, and in general a more facile, simple and economical apparatus is attained as the essential object of the invention.

The invention consists in certain novel combinations and arrangements of parts whereby a combined automobile for surface traveling and flying machine for navigating the air is furnished, and the combined features or characteristics of the apparatus enable the operator to secure a "flying start" when ascending into the air for aerial navigation.

In the accompanying drawings I have illustrated one complete embodiment of the physical structure constituting my invention constructed according to the best mode I have so far devised for the practical application of the principles.

Figure 1 is a plan view of the flying machine complete. Fig. 2 is a side elevation of Fig. 1. Fig. 3 is a front view of Fig. 2. Fig. 4 is a sectional view of the machine, parts being omitted for convenience of illustration. Fig. 5 is a view of the adjusting apparatus employed in connection with the action of ascending for aerial navigation. Fig. 6 is a detail of construction of one of the frame ribs, and connections.

In the preferred embodiment of the invention as illustrated I provide a frame supported upon the two traction wheels 1 and 2 and the steering wheel 3. The frame 4 is of the outline shown, and is preferably covered with a canvas covering 6 having side windows 7 and front window 8. The canvas covered frame is essentially a car, inasmuch as it is supported upon the traction wheels and the steering wheels, and is adapted to travel over surfaces similar to other automobile vehicles.

A motor 9 is mounted adjacent the driv-

ing shaft or axle 10 upon which the two traction wheels 1 and 2 are journaled, and the car may thus be driven through the medium of a countershaft 11, bevel gears 12 and 13, and a second pair of similar gears 14 and 15, as will be understood. The bevel gears 13 and 14 are supported on the vertical stud shaft 16 which is journaled in the bracket 17. The rotation of the wheels 1 and 2 may be controlled by the clutch 18 which is located on the countershaft 11 and adapted to co-act with the gear 12, and is supported from the bracket 19 which also supports the countershaft 11.

The steering wheel 3 is provided with a post 20 which is incased in a bracket 21 integral with the frame of the car. In Fig. 5 it will be clearly seen that the bracket is formed with an integral spool 22 about which a sleeve 23 may rotate. This spool has pivoted thereto the lower end of a link 24, which at its upper end is pivoted as at 25 to the lever arm 26. The lever 26 is pivoted in a shield 27 formed at the upper end of the post 20, and a rack 28 is provided for use in connection with the usual ratchet device 29.

From the above description it will be understood that as the car travels over a surface it may be steered laterally by means of the lever 26 and post 20, and also that by means of the lever 26 and connections the forward end of the car may be raised or lowered with relation to the post 20, with the shaft 10 as a pivotal center.

The car may be drawn forward by the action of the front propeller 30 on the shaft 11, or, when the clutch 18 is in operative position, the car may be driven by the traction wheels 1 and 2 through the mechanism described.

A seat 31 properly supported from the frame is provided for the operator, who is to sit within the canvas covered car, and may make observations through the windows at the sides and front of the car.

The wheels 1 and 2 are adapted for use not alone as traction wheels, but as driving wheels also, the wheels being used for the latter purpose when the machine is under aerial navigation. The driving wheels are intended to actuate the side wings 32 and 33. These wings are provided with braces or ribs 34 over which canvas covers 35 are spread, and at their lower ends each rib is provided with an eye 36 which is loosely

connected to an eye-bolt 37 secured by nut 38 in the bar 39 of the car frame. A horizontal brace or bar 40 is extended across each wing, and between these bars a member that I term a "fly sheet" 41, is arched upwardly, and connected to the top of the wings. The wings and fly sheet are actuated as shown in dotted lines Fig. 3, by means of connecting rods 42, 42. A pair of 10 these rods is located at each side of the machine, and each pair is connected to a head 43 which is in turn pivoted on the crank bar 44 of wheel 1 and wheel 2. At their upper ends the rods 42 are connected by eye bolts 15 44 with the wings, and it will be understood that the joints at both ends of the connecting rods are loose and permit a free movement of the rods.

A steering rudder 45 is located at the rear 20 of the machine. This rudder consists of a flexible cloth attached to the side bars 46, 46, which are pivoted in the frame at 47, and vertically movable independent of each other. Friction devices 48 are provided in 25 order to prevent displacement of the rods or bars when once adjusted.

The action of the rear rudder will be apparent. When the machine is navigating the air, by holding the two bars parallel, the 30 rudder is capable of steering the machine to ascend or descend. With the bars parallel the rudder presents a flat surface for contact with the atmosphere, but with one bar raised and the other lowered, as in Figs. 2 35 and 4, it will be seen that the machine may be caused to descend laterally, or ascend laterally. In the latter position the rudder is inclined to either one side or the other, and presents an oblique or inclined surface 40 for contact with the atmosphere.

In operating the machine, the motor is started and the car is driven over the surface by the traction wheels 1 and 2 and is steered by wheel 3. Through the action of 45 the connecting rods, the wings and fly sheet are actuated, and the car is lifted from the supporting surface. Now with the front propeller rotating the car is propelled forward through the atmosphere. To assist in 50 ascending, the front portion of the car may be lifted as explained, with the rear axle as

a pivot, and while running over the ground, an impetus is given to the car to rise. The car is sustained by the wings and air sheet, and may be caused to ascend or descend, 55 while in the air, by the action of the rear rudder, or may be caused to ascend or descend in an oblique direction by means of the rear rudder as described.

Having thus fully described my invention, 60 what I claim is:—

1. The combination with a car having a rear axle and driving wheels, a hollow bracket, a steering post supported in the bracket and a wheel in said post, a sleeve 65 retained on the bracket and a link pivoted on the sleeve, and a lever pivoted to the link and post, whereby the forward part of the car may be moved relatively to the steer wheel with the rear axle as the center of 70 motion.

2. The combination with a car having a driving shaft and driving wheels with crank heads thereon, of a pair of flexible wings loosely connected to the car and projecting 75 upwardly and outwardly therefrom, a front propeller wheel and a rear rudder, rods connecting the wings and crank heads, and means for actuating the shaft and propeller.

3. The combination with a car having a 80 driving shaft and wheels, of a pair of flexible wings having their inner lower ends loosely connected to the car and projecting upwardly and outwardly from the car, connecting rods extending from each wheel to 85 a wing, and a flexible fly sheet located centrally of the car and extending in a curve from one wing to the other.

4. The combination with a car having a driving shaft, propeller, rudder, and driving 90 wheels, wings loosely connected to the car, connecting rods from the drive wheels to said wings, means for actuating the shaft and propeller, and a flexible fly sheet located above the wings and fastened at each 95 end to one of the wings.

In testimony whereof I affix my signature in presence of two witnesses.

DAVID S. THOMAS.
